ELECTRICALLY OPERABLE HORN

Robert Hesketh Purden, Birmingham, England,
assignor to Joseph Lucas Limited, Birmingham,
England

Application February 26, 1947, Serial No. 730,999
In Great Britain March 15, 1946

2 Claims. (Cl. 177—7)

1

This invention relates to motor vehicle and other horns of the kind in which the air column is contained in a spiral sound cavity terminating at one end in an open mouth, and in which the required vibrations in the air column are produced by a vibratory diaphragm, the latter being actuated by an electromagnet. The object of the invention is to provide an improved construction enabling a more compact design to be obtained than heretofore.

The invention comprises the combination of a body part formed with a spiral sound cavity, and an electromagnet accommodated within a bore formed at the centre of the said cavity.

In the accompanying drawings:

Figure 1 is a sectional side elevation and Figure 2 an inverted plan (with end cover removed) showing a horn constructed in accordance with the invention.

In carrying the invention into effect in the manner shown by the drawings, I employ a circular and shallow body part *a*, the diameter and thickness (or axial length) of which is sufficient to permit the formation therein of the required spiral sound cavity *b*. The outer end of this cavity terminates in a flared mouth piece *c*. For convenience of manufacture the spiral cavity is open to a flat side of the body part, and is closed by a cover flat plate *d* attached to that side. The cavity *b*¹ shown in the drawings forms no part of the sound cavity *b* and serves only to reduce the mass of metal required in the body part. But if it is desired to give the horn a lower pitched tone, the cavity *b*¹ may form an extension of the sound cavity *b*. In this case the bridge piece *b*² separating the cavities *b*, *b*¹ is machined out. The vibratory diaphragm *e* is secured at the other side of the body part, and the make-and-break device *f* which controls the electromagnet is located outside the diaphragm, this device being enclosed by a cover piece *g* detachably secured to the body part. The region bounded by one side of the diaphragm communicates with the inner end of the spiral cavity *b* through an opening *h* (Figure 2). It will be understood that when the cavity *b*¹ forms an extension of the cavity *b* as above described the opening *h* will be arranged at the end of the cavity *b*¹ remote from the cavity *b*.

The essential feature of my invention resides in the mode of accommodating the electromagnet. According to my invention I form in the body part *a* a bore situated at the centre of the spiral cavity, that is to say this bore is surrounded by the said cavity, and the electromagnet

(consisting of an iron core *i* and surrounding winding *j*) is mounted in this bore, the core *i* being adjustably secured to the cover plate *d* by a screw-thread connection and lock nut *k*. The required magnetic action to be exerted on the diaphragm *e* is effected through the medium of an iron armature *m* attached to the centre of the diaphragm and situated adjacent to one end of the core *i*.

10 By so arranging the electromagnet, I am able to effect a desirable reduction in the overall dimensions of a horn for a given duty, and thus obtain a more compact design than is practicable with the constructions hitherto employed.

15 Having thus described my invention what I claim as new and desire to secure by Letters Patent is:

1. An electrically operable horn comprising in combination a body part formed with a spiral tubular sound cavity around a central bore, an electromagnet having an iron core and accommodated within the bore in the body part, and a diaphragm situated at one side of the body part, the inner end of the cavity being in communication with the region bounded by the inner side of the diaphragm, and the outer end of the cavity being open.

2. An electrically operable horn comprising in combination a body part formed with a spiral sound cavity around a central bore, an electromagnet having an iron core and accommodated within the bore in the body part, a diaphragm situated at one side of the body part, and a cover plate attached to the body part and closing one side of the cavity, the inner end of the cavity being in communication with the region bounded by the inner side of the diaphragm, and the outer end of the cavity being open.

ROBERT HESKETH PURDEN.
